UNITED STATES PATENT OFFICE.

MARION LAWSON ROBINSON, OF ATLANTA, GEORGIA.

HORSE-DETACHER.

SPECIFICATION forming part of Letters Patent No. 725,367, dated April 14, 1903.

Application filed August 9, 1902. Serial No. 119,111. (No model.)

To all whom it may concern:

Be it known that I, MARION LAWSON ROBINSON, a citizen of the United States, residing at Atlanta, in the county of Fulton and State of Georgia, have invented a new and useful Horse-Detacher, of which the following is a specification.

This invention is an improved construction of horse-detacher, the object being to provide a simple appliance which can be attached to vehicles for the purpose of releasing the shaft or thills whenever the horse becomes unmanageable, thereby permitting the horse to escape without damaging the vehicle or its occupants.

Another object of the invention is to provide the shafts or thills with rolling supports, which will protect the thill-iron from damage after the horse has been detached from the vehicle.

Another object is to provide a thill-fastener in connection with the detaching mechanism, which fastener shall be of such construction that the thill-iron can be connected and disconnected without operating the detaching mechanism.

With these and certain other objects in view the invention consists in the novel features of construction, combination, and arrangement, all of which will be fully described hereinafter, and pointed out in the claims.

In the drawings forming part of this specification, Figure 1 is a perspective view, partly in section and illustrating the practical application of my invention. Fig. 2 is a vertical sectional view showing the operating-lever as locked in an inoperative position. Fig. 3 is a similar view showing the lever raised and operating for the purpose of detaching the shafts from the vehicles. Fig. 4 is a sectional view, partly in elevation, showing the thill-coupling mechanism. Fig. 5 is a front view of the same.

In carrying out my invention I employ a tubular bar A, which is cut away upon its forward side at the lower end and connected to the front face of the front axle, as shown at A'. A rod B works in the tubular portion of the bar A, and its lower end projects downwardly a short distance below the tubular portion of said bar; and connected to said

lower end are the links C, which links are pivotally connected to the inner ends of the flat bars D, which slide in guiding clips D', secured to the front face of the axle. These flat bars D carry an angular locking-pin E at their outer ends, the free end of said pin being adapted to engage the transverse horizontal aperture extending through the coupling-block F, said block being securely bolted to the under side of the axle by means of the clip F'. The forward end of this block is recessed, as shown at F², and fitting into said recess is the coupling member G, which is essentially in the form of a link and having a spring-actuated section G', which opens outwardly for the purpose of permitting the head H' of the thill-iron H to be inserted in the said coupling member. Locking-pin E, which passes through the block F, passes also through the coupling member G and normally holds the said member in the recessed portion of said block. When, however, the rod B is forced downwardly, the flat bars D are pushed outwardly through the medium of the links C, and the locking-pins E are disengaged from the coupling members G, and the said members, together with the shafts or thills, are completely detached from the vehicle, it being understood, of course, that said detachment only occurs when the rod B is thrown downwardly, and then takes place only when the horse becomes unmanageable and it is desired to detach him from the vehicle in order to prevent damage.

To operate the rod B, I employ a lever I, pivoted at I', having an eccentric head I², which bears upon the upper end of the rod B. The lever I works in the longitudinally-slotted portion A² of the bar A, and the rod B has transverse guide-pins B', which work in the transverse slots B², produced also in the upper end of the tubular bar A. A spring K is interposed between the bar A and the free end of the lever I, and the strap L is employed for holding the lever in an inoperative position, as most clearly shown in Figs. 1 and 2.

In order to provide against damaging the thill-irons and coupling member after the horse has been detached, I arrange depending bails M upon the shaft or thill, said bails carrying rollers M' at their lower ends, which contact with the ground, and thereby pre-

vent the thill-iron and coupling member coming into contact with the ground, and consequently saving the said parts from damage.

It will thus be seen that I provide an exceedingly simple and efficient construction of horse-detacher which can be applied to any of the vehicles now in use and which will operate to accomplish all the objects hereinbefore mentioned.

Having thus fully described my invention, what I claim as new, and desire to secure by Letters Patent, is—

1. The combination with the thill-irons of the coupling members having each an outwardly-opening spring-actuated section the coupling-blocks having recesses to receive the ends of the coupling members, the locking-pins, and means for operating the locking-pins, for the purpose of releasing the coupling members, as specified.

2. In a device of the character described, the combination with the thill-irons, a link member having a spring-section, a recessed

coupling-block adapted to receive said link member, means for securing said link in the recess of the block, means located on the vehicle for releasing said links and detaching the thills from the vehicle, and means carried by the thills adapted to prevent their contact with the ground when detached.

3. The combination with the tubular bar attached to the axle, the rod movable therein, the lever for operating the said rod, and means for holding the lever in an inoperative position the links connected to the lower end of the rod, the flat bars slidably arranged upon the axle and connected to the links, the angular pins carried by the outer ends of the sliding bars, the coupling-bars through which the pins work, the coupling members and the thill-irons, all arranged and adapted to operate as specified.

MARION LAWSON ROBINSON.
